(57) **CLAIM**

The ornamental design for personal stimulation device, as shown and described.

DESCRIPTION

FIG. 1 is a perspective view from above and toward the left side of a first embodiment of a design for a personal stimulation device;

FIG. 2 is a top plan view of the first design embodiment;

FIG. 3 is a bottom plan view of the first design embodiment;

FIG. 4 is a front elevational view of the first design embodiment;

FIG. 5 is a rear elevation view of the first design embodiment;

FIG. 6 is a right end elevation view of the first design embodiment;

FIG. 7 is a left end elevation view of the first design embodiment;

FIG. 8 is a perspective view from the front and toward the right side of a second embodiment of a design for a personal stimulation device;

FIG. 9 is a front elevation view of the second design embodiment;

FIG. 10 is a back elevation view of the second design embodiment;

FIG. 11 is a top plan view of the second design embodiment;

FIG. 12 is a bottom plan view of the second design embodiment;

FIG. 13 is a right end elevation view of the second design embodiment; and,

FIG. 14 is a left end elevation view of the second design embodiment.
